UNITED STATES PATENT OFFICE.

AARON M. WEBER, OF OSHKOSH, WISCONSIN.

DESIGN FOR AN EYE.

SPECIFICATION forming part of Design No. 25,991, dated September 8, 1896.

Application filed August 4, 1896. Serial No. 601,674. Term of patent 14 years.

To all whom it may concern:

Be it known that I, AARON M. WEBER, a citizen of the United States, residing at Oshkosh, in the county of Winnebago and State of Wisconsin, have invented and produced a new and original Design for an Eye; and I do hereby declare the following to be a full, clear, and exact description of the same, reference being had to the accompanying drawings, forming a part thereof.

Figure 1 shows in top plan view an "eye" embodying my design. Fig. 2 is an edge view.

My design for an eye consists of the shape

substantially as shown, which shape comprises the substantially triangular portion *d*, the bends at *c*, forming the contracted neck portion, and the laterally-enlarged portion *b*.

I claim—

The design for an eye, substantially as shown and described.

In testimony whereof I affix my signature in presence of two witnesses.

AARON M. WEBER.
